Inventor:

Erich Richter.

UNITED STATES PATENT OFFICE.

ERICH RICHTER, OF ZITTAU, GERMANY.

ORNAMENT FOR BOBBED HAIR.

Application filed August 9, 1928. Serial No. 298,508.

Hair ornaments of various types have become known. Some of said ornaments are fastened in the hair by means of pins and other ornaments are fixed by hooking or screwing into a support. With the latter kind of hair ornament it happens easily that hairs are caught in the fixation so that the hair dress gets into disorder. These kinds of ornaments are further adapted only for long 10 plaited and knotted hair.

This invention relates to hair ornaments free from said inconveniences specially designed for modern bobbed hair.

The hair ornament consists of a support, 15 designed to be placed under the hair and carrying sleeves into which pieces of jewelry and the like can be inserted by plugs, short pins projecting from the lower surface of the piece of jewelry bearing with a slight pressure 20 against the scalp so that the hair dress remains in order and is securely held by the ornaments.

An embodiment of the invention is illustrated by way of example in the accompanying drawing, in which

Fig. 1 shows the hair ornament in perspective view.

Fig. 2 is a section through a piece of jewelry.

On a resilient bow *a*, shaped in accordance 30 with the shape of the head and made of elastic material, sleeves *c* are fixed designed to hold the pieces of jewelry *e* by means of plugs *d* to be inserted into said sleeves. One or 35 several such sleeves *c* might be mounted on arms *b* projecting in any suitable direction from the bow *a*. The resilient bow *a* is placed

on the head so that it is covered by the hair. Only some of the sleeves might be used for holding pieces of jewelry.

On the lower surface of the piece of jewelry *e* short studs *f* of suitable material, specially of rubber are arranged, preferably at the ends of the piece of jewelry and standing perpendicular to the same so that, when the piece of jewelry has been inserted in the sleeve *c*, these studs *f* bear with slight pressure against the scalp and prevent slipping out of certain portions of the hair so that the hairdress is kept in order.

I claim:—

1. A hair ornament for bobbed hair, comprising in combination a resilient bow of elastic material shaped in accordance with the shape of the head, sleeves fixed on and projecting from said bow, and pieces of jewelry having each a plug projecting from the lower surface designed to be inserted into one of said sleeves.

2. A hair ornament for bobbed hair, comprising in combination a resilient bow of elastic material shaped in accordance with the shape of the head, sleeves fixed on and projecting from said bow, pieces of jewelry having each a plug projecting from the lower surface designed to be inserted into one of said sleeves, and studs of soft material like rubber projecting from the lower surface of the piece of jewelry so that they bear with slight pressure against the scalp when the piece of jewelry has been inserted into a sleeve.

In testimony whereof I affix my signature.
ERICH RICHTER.
